DESIGN FOR A CANDELABRA OR SIMILAR ARTICLE

Will Cameron McCartney, Cambridge, Ohio

Application January 21, 1937, Serial No. 67,194

Term of patent 7 years

To all whom it may concern:

Be it known that I, Will Cameron McCartney, a citizen of the United States of America and resident of Cambridge, county of Guernsey, and State of Ohio, have invented a new, original, and ornamental Design for a Candelabra or Similar Article, of which the following is a specification, reference being had to the accompanying drawing, forming part thereof, in which—

Figure 1 is a top plan view of a candelabra or similar article, showing my new design; and—

I claim—

The ornamental design for a candelabra or similar article, substantially as shown.

WILL CAMERON McCARTNEY.
